INK FOUNTAIN

Edward F. Dudley, Oak Park, Ill., assignor to
Miehle Printing Press & Manufacturing Company, Chicago, Ill., a corporation of Illinois

Application November 17, 1938, Serial No. 240,913

14 Claims. (Cl. 101—350)

This invention, which relates to inking mechanism for printing presses in general, has for its principal object the provision of an improved ink fountain which is more particularly adapted for use on printing presses of the power plate type.

A more specific feature of my invention resides in means whereby the thickness of the film of ink to be supplied to a printing plate may be very readily and accurately controlled.

Other important features of the invention will become apparent from the following description and appended claims read in conjunction with the accompanying drawings of which:

15 Figure 1 is a diagrammatic illustration of the principle of the invention and showing the general arrangement of the cooperating rollers and other parts;

20 Figure 2 is a side elevation of the ink fountain unit in partial cross section; and

Figure 3 is a view in elevation of the unit taken from the right hand side of Figure 2.

The ink fountain arrangement, as illustrated diagrammatically in Figure 1, includes upright end frame pieces 10 which support the roller unit. The fountain unit proper consists of three rollers, namely a large fountain or distributing roller 11 and two cooperating rollers 12 and 13 of smaller diameter and both of which, as will be hereinafter explained, are mounted adjustably with relation to the surface of roller 11. By means of the latter roller the ink is transferred to the inking-in roller 14, the surface of which is of any suitable composition such as rubber and which roller in turn applies the film of ink to the printing plate 16 as it passes beneath it. The circumference of the roller 14 is greater than the length of the maximum size plate to be used, in order to prevent any part of the circumference of this roller from "repeating" on even the maximum size plate.

45 The roller 12 acts in the same capacity as the fountain blade in the regular, commonly known inking mechanisms, namely it controls the film of ink to be applied to the surface of the fountain roller 11. The roller 13 takes the place of the back blade found in fountains used heretofore on power plate presses.

As is shown in Figure 1, the rollers 12 and 13 are so arranged that there will be a gap between them and the roller 11, the gap between rollers 13 and 11 being somewhat wider than between rollers 12 and 11. The main purpose of roller 13 is to form an ink retaining space together with rollers 11 and 12, which is particularly desirable when a somewhat fluid ink is used, in which case a greater volume of ink must be placed into the fountain than when a heavy ink is used. During the operation of the press, heavy ink, if in 55 small quantity, will gather in the form of a "roll"

of ink between the fountain roller 11 and roller 12, as indicated at 16, therefore, in such event the roller 13 will lose its regular function and could be omitted.

In order to pre-rub the ink before it is transferred to the inking-in roller 14, the roller 12 is geared so that its surface speed shall be considerably slower than that of roller 11, thereby giving an ink mill effect which will assure satisfactory distribution of the ink.

10 The surface speed of roller 13 is slightly faster than that of the fountain roller 11 for the purpose of preventing any tendency for even a rather thin ink from leaking backward out of the fountain through the gap between rollers 15 13 and 11.

A scraper blade 15 is arranged above the roller 13 and adjusted in close proximity to its surface so that during the rotation of the roller it will scrape off any ink carried upwardly by the roller, 20 thereby retaining the ink within the fountain i. e. the space between rollers 11, 12 and 13.

25 Referring now to Figures 2 and 3 of the drawings which illustrate the fountain construction in more detail, it will be apparent that the fountain unit proper, namely rollers 11, 12 and 13 are mounted in a separate frame so that they can be adjusted as a whole relative to the inking-in roller for the purpose of maintaining proper contact between the fountain roller 11 and the latter roller.

The end pieces 17 of the fountain unit frame are connected together by means of girts 18 so that when all the parts are assembled, they will form a separate unit. This unit is mounted between the upright side frames 10 and is provided with lugs 19 and 20 which extend into a guide slot 21 formed in the uprights 10. The rollers 11, 12 and 13 will be snugly fitted between the end pieces 17 and spring pressed plates 22, see Figure 40 3, are placed between the end pieces and the end faces of the rollers to insure against leakage of ink at the ends of said rollers. The roller 12 is carried by journal bearings 23 which are slidably mounted within slots 24 provided in the end 45 pieces 17. Coil springs 24 urge said journal bearings upwardly against adjusting screws 25 by means of which the roller 12 can be adjusted vertically in order to provide the proper gap or clearing between it and the fountain roller 11, the latter being mounted in journal bearings provided in the lugs 20.

55 It is important of course that the adjustment of the roller 12 be done very accurately, therefore I provide a micrometer scale 26 on the screw 25 so that by means of an indicator 27 the operator can readily observe the extent of adjustment that has been made.

The roller 13 is mounted in a similar manner 60

to the roller 12 and the means for adjusting it are also identical.

For the purpose of adjusting the entire fountain unit in a vertical direction with relation to the inking-in roller 14, an adjusting screw 28 is threaded into the cross bar 29 and projects downwardly and through a bore in the lug 19. To the lower end of said screw is secured a collar 33 which snugly fits into the gap between the lugs 19 and 20. It will be seen therefore that by turning the screws 28 at each end of the fountain unit, the entire unit can be adjusted upwardly or downwardly.

By means of the indicator 31 and the scale 32 on the set screw 28, the position of the fountain unit, i. e. the fountain roller 11, with relation to the roller 14 can be readily observed.

A lock nut 30 is provided on the screw 28 so that the fountain unit can be securely locked in its adjusted position.

The inking-in roller 14 also may be adjusted vertically and independently of any of the other rollers. This is accomplished by means of the set screw 33' which is threaded into the upright frame 10 and the head of which bears against the lower face 34 of the journal bearing 35. The screw 33 is so set that when the roller 14 rolls over the printing form, there is a slight clearance between it and the face 34. This will assure the desired rolling contact while the form is being inked in.

The extent of upward movement of the roller 14 is limited by means of the head 36 of the adjusting screw 37 bearing against the upper face 35 of the journal bearing 35. The screw 37 is threaded into a plate 38 which is bolted to the upright 10 by means of bolts 39 and 40.

It will be readily understood that without departing from the principle of my invention, many modifications could be adopted and therefore I desire to cover any departures of design that will come within the meaning of the appended claims.

I claim:

1. An ink fountain, having in combination a roller unit comprising an inking-in roller, an ink distributing roller, a roller cooperating with said latter roller to control the volume of ink to be supplied to said inking-in roller, and a second roller arranged adjacent said distributing roller to provide an ink retaining space together with said distributing roller and the other roller cooperating therewith.

2. An ink fountain, having in combination a roller unit comprising an inking-in roller, an ink distributing roller, a roller cooperating with said latter roller to control the volume of ink to be supplied to said inking-in roller, a second roller arranged adjacent said distributing roller to provide an ink retaining space together with said distributing roller and the other roller cooperating therewith, and means for adjusting said latter three rollers as a unit with respect to said inking-in roller.

3. An ink fountain, having in combination a roller unit comprising an inking-in roller, an ink distributing roller, a roller cooperating with said latter roller to control the volume of ink to be supplied to said inking-in roller, and rotating at a slower rate of speed than said distributing roller, and a second roller having a greater surface speed than said distributing roller and arranged adjacent said distributing roller to provide an ink retaining space together with said distributing roller and the other roller cooperating therewith.

4. An ink fountain, having in combination a

roller unit comprising an inking-in composition roller, an ink distributing steel roller, a steel roller cooperating with said latter roller to control the volume of ink to be supplied to said inking-in roller, and a second steel roller arranged adjacent said distributing roller to provide an ink retaining space together with said distributing roller and the other roller cooperating therewith.

5. An ink fountain according to claim 4, in which both of the steel rollers which cooperate with the distributing roller are mounted adjustably.

6. An ink fountain, having in combination a roller unit comprising an inking-in composition roller, an ink distributing steel roller, arranged to supply a film of ink to said inking-in roller, an adjustable steel roller cooperating with said latter roller to control the volume of ink to be supplied to said inking-in roller and rotating at a slower rate of speed than said distributing roller, and a second adjustable steel roller having a greater surface speed than said distributing roller and arranged adjacent said distributing roller to provide an ink retaining space together with said distributing roller and the other roller cooperating therewith.

7. An ink fountain according to claim 6, in which are embodied means for adjusting the distributing and the two cooperating steel rollers as a unit in respect to the inking-in roller.

8. An ink fountain according to claim 2, in which the one roller which cooperates with the distributing roller rotates at a lower rate of speed than the surface speed of the latter, whereas the second roller cooperating with the distributing roller has a greater surface speed than the latter roller.

9. An ink fountain according to claim 8, in which the two rollers cooperating with the ink distributing roller are mounted adjustably.

10. An ink fountain according to claim 1, in which the ends of the distributing roller and of its two cooperating rollers are sealed in order to avoid leakage of ink.

11. An ink fountain according to claim 10, in which one of the two rollers which cooperate with the ink distributing roller rotates at a lower rate of speed than the surface speed of the latter, whereas the other roller which cooperates with said distributing roller has a greater surface speed than the latter.

12. An ink fountain according to claim 1, in which is embodied a scraper blade arranged to scrape surplus ink from the surface of the second roller which cooperates with the distributing roller.

13. An ink fountain having in combination a roller unit comprising an inking-in roller, an ink distributing roller, a roller cooperating with said latter roller to control the volume of ink to be supplied to said inking-in roller and rotating at a slower rate of speed than said distributing roller, a second roller having a greater surface speed than said distributing roller and arranged adjacent said distributing roller to provide an ink retaining space together with said distributing roller and the other roller cooperating therewith, and a scraper blade arranged to scrape surplus ink from the surface of said second roller.

14. An ink fountain according to claim 1, in which the circumference of the inking-in roller is greater than the maximum length of the printing form to be used.
